ROCKET DEVICE

Filed Nov. 20, 1943

UNITED STATES PATENT OFFICE

2,442,528

ROCKET DEVICE

John O. Beattie, New York, N. Y., assignor to
 Aerial Products, Inc., Merrick, Long Island,
 N. Y., a corporation of New York

Application November 20, 1943, Serial No. 511,034

7 Claims. (Cl. 102—35.6)

1

This invention relates to rocket propelled devices and more particularly to a device embodying a rocket propelled pyrotechnic candle or combustible illuminating member. The latter is adapted to be discharged from the body of the rocket device after the latter has achieved a predetermined height and to be suspended from a parachute as it drops to earth. The pyrotechnic candle is ignited as it is expelled from the body of the rocket casing, and in combustion which lasts for a predetermined time, emits light of great brilliancy for illuminating purposes.

A principal object of the invention is to provide a device of this character that will be effective for the purposes intended, and very simple and relatively cheap to manufacture.

A further object is to provide a device of this character that will be very simple to assemble on a mass production basis.

The rocket construction consists essentially of a rocket body assembly, and the pyrotechnic candle and parachute assembly. These sub-assemblies are assembled together to make a complete unit. The rocket body assembly embodies a casing providing a compartment for propelling charge, a propelling charge in the casing, a primer for firing the charge, means to direct the products of combustion outwardly of the compartment to impart propelling and rotary motion to the rocket body in flight, and a second casing adapted to receive the pyrotechnic candle and parachute assembly. The two casings are connected together to form a single body but are separated internally by suitable partitioning so that the combustion of the propulsion charge will not affect the pyrotechnic candle. The second casing also carries an expelling charge which is adapted to be fired by suitable timing or fuse means after the rocket has been propelled to a predetermined height. The firing of the expelling charge causes expulsion from the second casing of the pyrotechnic candle and parachute and simultaneous ignition of the pyrotechnic mix of the candle so that as the candle floats to earth its combustion emits light of great brilliancy, for example, up to 350,000 candlepower.

Since the rocket device rotates in its flight, a likelihood of relative rotation between the pyrotechnic candle and the second casing as well as between the candle and its parachute exists. This must be avoided in order to prevent entanglement of the shrouds of the parachute with the suspension cable or cord. It is another

2

object of the invention therefore to provide simple means for avoiding such entanglement.

To the accomplishment of the foregoing and such other objects as may hereinafter appear, this invention consists in the novel construction and arrangement of parts hereinafter to be described and then sought to be defined in the appended claims, reference being had to the accompanying drawing forming a part hereof, 10 which shows, merely for the purposes of illustrative disclosure, a preferred embodiment of the invention, it being expressly understood, however, that various changes may be made in practice within the scope of the appended claims, 15 without digressing from the inventive idea.

In the drawing in which similar reference characters denote corresponding parts:

Fig. 1 is a longitudinal section of the device; 20 Fig. 2 is a transverse section taken along line

2—2 of Fig. 1;

Fig. 3 is an enlarged transverse section taken along line 3—3 of Fig. 1;

Fig. 4 is a transverse section taken along line 4—4 of Fig. 1;

Fig. 5 is a bottom plan view of the device shown in Fig. 1;

Fig. 5a is a fragmentary section taken along line 5a—5a of Fig. 5;

Fig. 6 is a transverse section taken along line

30 6—6 of Fig. 1; and

Fig. 7 is an elevational view of the pyrotechnic candle and parachute assembly as it would appear in descent after separation from the rocket body.

Referring to the drawing, 10 denotes a rocket 35 tube preferably of seamless or welded cold-rolled steel tubing. The tube 10 is threaded internally at 11 and 12 adjacent its opposite ends. It preferably is provided with a zinc plating or other protective coating or covering. The tube

40 10 may be of other material.

An exhaust port or end plug, or bottom member 15 preferably of cold rolled steel is threadedly engaged in the threaded portion 11 of the tube 10. This plug 15 has a plurality of symmetrically spaced holes or vents 16. Each hole or vent 16 is inclined with respect to the axis of the plug. In the embodiment shown the angle of inclination is approximately 25°. (See Fig. 5a.) Other angles of inclination may be chosen. The purpose of these vents 16 will be presently described. This bottom plug 15 may be coated with zinc or other protective coating. The bottom plug 15 is bored at 17 to receive a conventional type of percussion-operated primer 18 which communicates by a vent

19 with the inside of the tube 10. The plug 15 may be of other material.

A partitioning member or top plug 20 preferably of cold rolled steel threadedly engages the threaded portion 12 of the tube 10. This top plug too may be of other material and may be zinc coated or covered with other protective coating. The plug 20 is provided with a threaded hole 21 into which a timing ferrule or tube 22 of cold rolled steel or other material is threaded. Preferably, the hole 21 is centrally located so that the ferrule 22 extends downwardly into and concentrically about the axis of tube 10. The ferrule or tube 22 is of much smaller diameter than that of tube 10.

The tube 10 contains the rocket propulsion charge which may be of any suitable type. In the embodiment shown the charge consists of a plurality of disc-like members or pellets 23 of compressed propulsion compound. These discs 23 are prepared as will be presently described and have centrally located axially extending holes 24 thereby providing a space into which the tube or ferrule 22 extends. A compression spring 25 is positioned between the bottom plug 15 and the lowermost disc or pellet 23. This spring serves to keep the discs 23 in position. The spring may be zinc coated or otherwise covered with a protective covering. The propulsion charge may be a cylinder of single grain smokeless powder.

The ferrule 22 is open at its bottom and provided with a restricted vent 26 at its upper end. This ferrule 22 is filled with a combustible fuse or timing compound 27. Such a compound, by way of example, may consist of a compressed solidified mixture of potassium nitrate, charcoal, sulphur and calcium carbonate in proportions to be presently described. This mixture or fuse compound 27 is compressed into the tube or ferrule 22 and is adapted to have a predetermined burning time for a purpose to be presently described.

A carrier casing or tube 30 is threadedly secured to the tube 10 at 31. The casing 30 preferably is of seamless or welded cold rolled steel tubing. Other suitable material may be employed. It need not be of as thick stock as that of tube 10 and as shown in the drawing has somewhat thinner wall thickness. This casing which constitutes an extension of tube 10 is adapted to carry the pyrotechnic candle, parachute and expelling charge therefor as will be described hereinafter.

A washer 32 of felt or other material is positioned in the casing 30 adjacent to the top plug 20. The central hole of this washer is filled with an expelling charge 33. Such charge may for example be unglazed black powder. Any other suitable composition may be used. This charge is retained in the washer by retaining discs 34, 35 of tissue paper or other material glued or otherwise fastened to the opposite faces of said washer 32 so that the felt washer and expelling charge 33 may be inserted as a unit into the casing 30.

A combustible illuminating member of pyrotechnic candle 38 is positioned in the casing 30 above the washer 32. This candle comprises a tubular casing 39 of "kraft" paper or other suitable material. The lower end of the casing is closed by a cap 40 of muslin or other suitable material. The candle casing 39 has a priming disc 41 of compressed priming compound to be presently described lying directly adjacent the cap 40. The latter is perforated at its center. The perforation is filled with additional priming compound 41a applied separately to the disc 41

in any suitable manner as by painting on a wet mixture of such priming compound. Overlying the priming disc 41 is a layer 42 of starter mixture to be presently described and overlying the layer 42 is the pyrotechnic mix 43 also to be presently described which is in solidified, compressed form.

The upper end of the candle casing is closed off by a plug 45 of wood or other suitable material. This plug 45 is secured to the pyrotechnic mix 43 as by glue and may be additionally secured by screws (not shown).

A candle stop member 47 of steel or other suitable material coated with zinc or other protective coating is secured to the inner face of casing 30 as by spot welding or the like. This member 47 serves as a reinforcing abutment for the head 48a of a nail or pin 48 that is driven through the wall of casing 39 into the wooden plug 45 to prevent rotary displacement of the candle 38 relative to the casing 30. The abutment or stop member 47 is especially necessary to take up the shock of discharge of the rocket at which time forces tending to produce relative rotation between the candle 38 and casing 30 will be of greatest magnitude. The nail or pin 48, however, is not of sufficient length or other dimensions to prevent discharge of the candle from the tube 30 when the expelling charge 33 is exploded as will be presently described.

30 A parachute anchor or bracket member 50 is secured to the block 45 as by screws 51 or the like. This member is substantially L-shaped and the vertical arm 52 extends into the space in case 30 above the candle 38. A parachute 54 in folded condition is positioned within the casing 30 above the candle 38. This parachute by way of example, may be a commercial baseball type, 16 shroud, 8 panel paper parachute. The suspending shrouds or cables 55 are joined together 40 and secured to a swivel 56 which in turn is secured as by asbestos cord 57 at 58 to the parachute anchor 50.

A washer 60 of felt or other desirable material is provided in the casing 30 below the parachute 54. This washer is designed to protect the parachute 54 from the products of combustion of the expelling charge 33.

The suspending cables 55 are packed about the anchor arm 52 without encircling it. A second 50 washer 60a of felt or the like overlies the packed shroud 55. A disc 61 of wax paper or other suitable material overlies the washer 60a and prevents absorption by the latter of any compound with which the parachute may have been heated. 55 A sleeve 62 of paper or the like surrounds the parachute 54. This sleeve facilitates packing and prevents contact between the parachute and the container 30. The parachute 54 is packed in conventional manner and positioned in the sleeve 62 about the anchor arm 52 so that rotation of candle 38 will necessarily rotate the parachute and thereby prevent any entanglement of the shrouds 55 and anchor arm 52.

65 A nose cap 64 of drawn sheet steel or other suitable material is provided to close the upper end of casing 30. The cap 64 is coated with zinc or other protective coating. It has convex shape to provide a bluntly-pointed nose for the assembled device and is adapted to be retained on the casing 30 frictionally so that it will be pushed or blown off when the expelling charge 33 is fired.

In the embodiment shown, a cup-like member 65 is secured to the inner face of the nose 64 as by spot-welding or the like. This cup-like member 65 of the same material as member 64 ex-

tends outwardly of the latter at 66. The portion 66 has a diameter admeasured to frictionally engage within the upper end of casing 30. The top 61 of the member 65 acts to prevent the parachute 54 from being driven into the pointed portion of the nose cap 64.

In operation, the projectile described is adapted to be fired from a mortar having a firing pin. When the projectile is dropped onto the firing pin in the mortar, the pin strikes the primer 18 exploding the latter. This explosion ignites the propelling compound or propulsion charge 23 and at the same time ignites the timing charge or fuse 27 in the ferrule 22. The products of combustion of the propelling compound 23 vent through the vents or orifices 16 in the base plug 15, driving the projectile from the mortar and to a high elevation. The angular disposition of the vents 16 causes the projectile to whirl about its longitudinal axis during flight. When the projectile achieves a predetermined height between 1400 to 1600 feet in the embodiment shown, the timing or fuse compound 27 has burned out so as to ignite the expelling charge 33. The latter explodes and drives the candle 38 and parachute 54 outwardly of the forward end of casing 30 blowing or pushing off the nose cap 64 in such action. The top 61 of member 65 prevents the parachute from being blown into the member 64. At the same time, the explosion of the expelling charge 33 fires the priming pellet 41 of the pyrotechnic candle 38, which in turn ignites the starter mixture 42 thereof and, in turn, causes the pyrotechnic mix 43 to burn from the bottom up as the candle 38 falls. The fall of the candle is retarded by the parachute 54 from which it is suspended and which then opens so that the burning candle 38 falls slowly to earth. The pyrotechnic mix 43 is of such composition that it burns for a minimum time of about 1 minute with a brilliancy of at least 350,000 candle power.

The discs or pellets 23 of the propulsion charge may be composed of the following materials:

	Per cent
Potassium nitrate	75
Charcoal	15
Sulphur	10

in finely divided form constituting a meal. This meal is mixed with calcium carbonate in the following proportions: meal 16 parts, calcium carbonate 2 to 6 parts. This mixture is mixed thoroughly and molded under pressure in molds to produce the discs or pellets 23.

The proportion of parts and percentages is by weight.

The timing or fuse compound 27 may consist of a mixture of 16 parts by weight of the above described meal and 3½ parts by weight of calcium carbonate. This mixture after thorough rumbling to insure homogeneity of mix is incorporated into the ferrule by pressing successive increments of the mix into the ferrule under static loads of 2000 lbs. In the embodiment shown, eight successive increments each increment loaded under the same conditions have been incorporated into the ferrule 22. The burning time of the timing compound can be anything desired depending upon the length of the ferrule. In the embodiment shown, the burning time is approximately seven seconds plus or minus one second.

The priming disc or pellet 41 of the pyrotechnic candle may consist of a homogeneous mixture of finely divided

	Parts
Potassium nitrate	12
Willow charcoal	8
Sulphur	2
5 Dextrin	1½

The homogeneous mixture is dampened with water and pressed in a mold under a static load of 1000 lbs. into the solid disc 41. The priming composition 41a is of the same material but simply painted onto the disc 41. The proportions are by weight.

10 The starter mixture 42 may comprise a homogeneous mixture of equal parts by weight of fused silicon and potassium nitrate both in finely divided form.

15 The pyrotechnic mix 43 comprises a homogeneous mixture in finely divided form of

	Parts
Linseed-oil coated magnesium	48
20 Barium nitrate	35
Grain aluminum	4
Calcium oxalate	12
Lithographic varnish	4

25 All parts are by weight.

20 The magnesium is coated with the linseed oil at least 48 hours before its incorporation with the remainder of the pyrotechnic mix. This is very important. The lithographic varnish is homogeneously mixed with the barium nitrate.

30 The linseed oil-coated magnesium and barium nitrate-lithographic varnish mixture is then combined with the grain aluminum and calcium oxalate and mixed thoroughly.

35 This pyrotechnic mixture is then utilized to prepare the candle 38 as follows: The candle case 39 is placed into a mold. The priming pellet 41 is placed at the bottom of the case. Then a small quantity (about 1 gram in this instance)

40 of the starter mixture 42 is poured over the pellet 41. Then a first increment of the pyrotechnic mix 43 is placed in the candle case and pressed under a static load of 20,000 lbs. Nine more successive increments of pyrotechnic mix each com-

45 pressed under a static load of 20,000 lbs. are pressed into the case. Then hot glue is spread over the top increment and the wood plug 45 attached. Then the muslin disc 40 is glued over the bottom of the candle case 39, care being taken

50 to avoid glueing its central portion to the disc 41. The unglued portion of the muslin cap 40 is then cut out and the priming mix 41a painted on disc 41 to fill the opening left by the cut out portion of cap 40. The solid candle 38 is thus 55 produced for insertion as a unit into the casing 30.

While specific examples of propulsion, timing, priming, starting, and pyrotechnic compounds have been described herein, it is to be understood 60 that these are by way of example only. There is no intention of limitation to the specific ingredients or proportions mentioned as these will vary to meet different operating conditions.

It should be expressly understood that propellants other than black powder can be used. For 65 example, a smokeless powder cylinder can replace the discs 23. Any other suitable propellant can be used.

Moreover the primer 18, for example, is not the 70 only way of igniting the charge 23. Other means may be provided to ignite this propulsion charge. For example, squib ignition could be employed for igniting the propulsion charge from a distant point by electric current from a dry cell or 75 hand generator. The squib would be incorporated

in the casing 10 in place of the primer 18 and ignited when current is applied.

In the assembly, all threaded joints are sealed in usual manner by the use of white lead or the like (not shown). This is especially important in connection with the threaded joints between the partitioning member 32 and the tubes 10 and 22 so as to prevent leakage of the combustion gases of the propulsion charge 23 into the candle casing 30. If such leakage occurred, premature explosion of the expelling charge 33 and ignition of candle 38 would take place. The partitioning member 32 is of sufficient strength to resist any tendency of the combustion of the propulsion charge 23 to drive it forwardly.

The material of the various parts while specified particularly may be changed to meet different operating conditions.

While specific structural details have been shown and described, it is to be understood that variation in structure and of materials within the scope of the appended claims is contemplated. There is no intention of limitation to the exact details shown and described.

What is claimed is:

1. In a device of the character described, a tubular casing, rocket propulsion charge in said casing, means for firing said charge, an end plate having biased orifices for venting the products of combustion of said charge rearwardly of said casing and for imparting rotary motion to the flight of the device, a second casing secured to said first-named casing and providing a continuation thereof, a pyrotechnic candle in said second-named casing, means for separating said propulsion charge from said pyrotechnic candle, an expulsion charge in said second casing, means for igniting said expulsion charge at a predetermined time after said propulsion charge has been fired to expel said candle from said second casing, an anchoring member secured to said candle and having a portion extending forwardly thereof, a parachute positioned about said forwardly extending portion, suspending means connecting said parachute to said forwardly extending portion, an abutment carried by said second casing, and means extending from a portion of said candle for engagement with said abutment for preventing relative rotation of said candle with respect to said casing during flight of said device to prevent entanglement of the suspending means with shrouds of said parachute.

2. A rocket-propelled illuminating device comprising a casing having a compartment for rocket propulsion charge, and a second compartment, a plurality of discs of compressed rocket propulsion charge in said first-named compartment, a compression spring for maintaining the discs in position, an end member at the trailing end of said casing having angularly disposed passageways for discharging the products of combustion of said charge rearwardly and angularly to impart whirling motion to the device in flight, said spring lying between the said end member and the lowermost of said discs in said first-named compartment, percussion means for firing said charge carried by said end member, combustible illuminating means in solid form in said second compartment, a parachute therein attached to said combustible illuminating means, an expelling charge in said second compartment for discharging its contents forwardly of said casing and adapted in such expulsion to ignite said illuminating means, and time fuse means extending into said first-named compartment and adapted

to be ignited by the firing of said propulsion charge and to fire said expelling charge a predetermined time thereafter.

3. A rocket-propelled illuminating device comprising a multi-sectioned casing whose sections are separable, a compartment in one of said sections for rocket propulsion charge, a plurality of discs of propulsion charge in said compartment, a compression spring for maintaining said discs in position, a closure member at the trailing end of said compartment having angularly disposed passageways for discharging the products of combustion of said discs rearwardly and angularly to impart forward and whirling motion to the device in flight, said spring lying between the lowermost of said discs and said closure member, percussion means carried by said closure member for igniting said discs, a second compartment in another of said separable sections, a partitioning member completely separating said two compartments, an expelling charge in said second compartment adjacent to said partitioning member, time fuse means extending from said partitioning member into said first compartment and communicating with said second compartment, said time fuse means being adapted to be ignited by the combustion of said discs and to ignite said expelling charge a predetermined time after the ignition of said discs, a combustible illuminating member carried in said second compartment adjacent to said expelling charge, an anchoring member secured to said illuminating member, a parachute positioned about said anchoring member, coupling means for joining said anchoring member and said parachute, and a removable closure member for the leading end of said device, said illuminating member being ignited by the firing of said expelling charge and being expelled from said second compartment together with said parachute by the explosion of said expelling charge.

4. A rocket-propelled illuminating device comprising a casing, rocket propulsion charge in separate units of solidified form in said casing, means for firing said charge, a combustible illuminating member in said casing, means in said casing for maintaining said charge and said member separate and for preventing access to said member of the products of combustion of said charge, means for directing said products of combustion rearwardly and angularly relative to the axis of said device to propel it forwardly with a whirling motion, means for firing said charge, means for expelling said member from said casing a predetermined time after the firing of said charge, said combustible member being in solid form, a substantially L-shaped anchoring member one of whose arms is secured to an end of said combustible illuminating member and the other of whose arms extends forwardly of said end of said combustible illuminating member, a parachute positioned about said other of said arms, means joining said parachute to said other of said arms of said anchoring member, an abutment on said casing and means extending from a portion of said illuminating member for engagement with said abutment to prevent relative rotation between said casing and said combustible member during flight of the device and to avoid entanglement of said joining means with said anchoring means on expulsion of said combustible member and said parachute from said casing.

5. A rocket-propelled illuminating device comprising a casing having a compartment for rocket propulsion charge, and a second compartment,

rocket propulsion charge in said first-named compartment, a compression spring for maintaining the charge in position, an end member at the trailing end of said casing having angularly disposed passageways for discharging the products of combustion of said charge rearwardly and angularly to impart whirling motion to the device in flight, said spring lying between the said end member and the lowermost end of said charge in said first-named compartment carried by said end member, combustible illuminating means in solid form in said second compartment, a parachute therein attached to said combustible illuminating means, an expelling charge in said second compartment for discharging its contents forwardly of said casing and adapted in such expulsion to ignite said illuminating means, and time fuse means extending into said first-named compartment and adapted to be ignited by the firing of said propulsion charge and to fire said expelling charge a predetermined time thereafter.

6. A rocket-propelled illuminating device comprising a multi-sectioned casing whose sections are separable, a compartment in one of said sections for rocket propulsion charge, propulsion charge in said compartment, a compression spring for maintaining said charge in position, a closure member at the trailing end of said compartment having angularly disposed passageways for discharging the products of combustion of said charge rearwardly and angularly to impart forward and whirling motion to the device in flight, said spring lying between the lowermost end of said charge and said closure member, percussion means carried by said closure member for igniting said charge, a second compartment in another of said separable sections, a partitioning member completely separating said two compartments, an expelling charge in said second compartment adjacent to said partitioning member, time fuse means extending from said partitioning member into said first compartment and communicating with said second compartment, said time fuse means being adapted to be ignited by the combustion of said propulsion charge and to ignite said expelling charge a predetermined time after the ignition of said propulsion charge, a combustible illuminating member carried in said second compartment adjacent to said expelling charge, an anchoring member secured to said illuminating member, a parachute positioned about said anchoring member, coupling means for joining said anchoring member and said parachute, and a removable closure member for the leading end of said device, said illuminating member being ignited by the firing of said expelling charge and

being expelled from said second compartment together with said parachute by the explosion of said expelling charge.

7. A rocket-propelled illuminating device comprising a casing, rocket propulsion charge in solidified form in said casing, means for firing said charge, a combustible illuminating member in said casing, means in said casing for maintaining said charge and said member separate and for preventing access to said member of the products of combustion of said charge, means for directing said products of combustion rearwardly and angularly relative to the axis of said device to propel it forwardly with a whirling motion, means for firing said charge, means for expelling said member from said casing a predetermined time after the firing of said charge, said combustible member being in solid form, a substantially L-shaped anchoring member one of whose arms is secured to an end of said combustible illuminating member and the other of whose arms extends forwardly of said end of said combustible illuminating member, a parachute positioned about said other of said arms, means joining said parachute to said other of said arms of said anchoring member, an abutment on said casing and means extending from a portion of said illuminating member for engagement with said abutment to prevent relative rotation between said casing and said combustible member during flight of the device and to avoid entanglement of said joining means with said anchoring means on expulsion of said combustible member and said parachute from said casing.
